(57) CLAIM

The ornamental design for an outdoor floor fan, as shown and described.

DESCRIPTION

FIG. 1 is a front, top and right side perspective view of an outdoor floor fan, showing my new design;

FIG. 2 is a rear, bottom and left side perspective view thereof;

FIG. 3 is a perspective view thereof, shown in a position of use;

FIG. 4 is a front view of the outdoor floor fan of FIG. 1;

FIG. 5 is a rear view thereof;

FIG. 6 is a left side view thereof;

FIG. 7 is a right side view thereof;

FIG. 8 is a top plan view thereof; and

FIG. 9 is a bottom plan view thereof; and,

FIG. 10 is an enlarged detail view of portion 10 encircled in FIG. 1.

Broken lines illustrate portions of the outdoor floor fan that form no part of the claimed design. Dot-dash broken lines depict the boundaries of the enlarged view and form no part of the claimed design.
